TIME-OPERATED COIN-CONTROLLED
SIGNAL APPARATUS

Charles H. Martin, West Springfield, Mass.

Application August 28, 1939, Serial No. 292,171

6 Claims. (Cl. 194—78)

This invention relates to improvements in time-operated coin-controlled signal apparatus and is directed more particularly to a novel apparatus now known as a parking meter.

5 It is a principal object of the invention to provide a parking meter including a time mechanism that is under the influence of a coin-controlled mechanism and the construction is such that coins of varying denominations may be employed.

10 That is to say, according to this invention, a coin of certain denomination may be employed to set the timing mechanism for a certain period of time while another coin of different denomination may be employed to set the timing mechanism for a 15 shorter or longer period. As a special feature, a plurality of coins may be deposited to set the mechanism for a period of time totalling the periods affected by the several coins.

The apparatus of the invention is characterized 20 by a signal which is shiftable between signaling and non-signaling locations or positions by means of a timing mechanism which, as stated, is under the control of a coin-actuated mechanism. In its broad aspects, the parking meter construction of 25 the invention is such that the operator of a vehicle may deposit a coin or coins in the apparatus and set the time mechanism in operation to locate the signal in one position with the signal movable to another position at the expiration of a definite 30 length of time depending upon the coin or coins deposited.

By reason of its novel construction, the timing mechanism never needs to be wound as is the case with the so-called "full automatic" parking meters 35 known in the art. At the same time, I retain all the advantages of such meters and provide an arrangement whereby the parker need only deposit the desired coin or coins in a single slot and the coins automatically set the device in operation 40 for the allotted period of time.

It is also an object of the invention to provide a parking meter having a movable signal which is adapted to visibly indicate whether the vehicle is rightfully parked. As will appear, the coin 45 mechanism winds the clock mechanism to run as many minutes as the motorist is allowed for his coin or coins and when the time is up, the clock mechanism stops and a signal immediately becomes visible to indicate the fact.

50 Some of the advantages of the construction of this invention is that the time periods are flexible. That is to say, any time or price arrangement can be set up as contrasted with the usual practice of setting a definite period of one hour for the 55 deposit of a single coin, such as a nickel, and of

permitting the deposit of one coin only at a time.

According to my invention, the meter may be set to give, say twelve minutes for one cent, twenty-four minutes for two cents, three times twelve minutes for three cents, and so on or to give one hour for five cents, two hours for two nickels and so on. The pennies and/or nickels for the time one wishes to stay may all be deposited at one time, which is not possible with meters heretofore known.

5 It is a still further object of the invention to provide an apparatus where the last coin deposited is in full view until another coin is deposited to take its place. This effectively prevents the use of slugs as is desirable from the 15 point of view of the city government, at least.

Various other novel features and advantages of the invention will be hereinafter more fully referred to in connection with the accompanying description of the invention, in the present preferred 20 form thereof, reference being had to the accompanying drawings wherein:

Fig. 1 is a front elevational view of the parking meter of the invention;

Fig. 2 is a side elevational view of what is shown 25 in Fig. 1;

Fig. 3 is a front elevational view of the meter of the invention with the outer casing removed to explain certain novel features;

Fig. 4 is an end elevational view of the coin-receiving member;

Fig. 5 is a plan view of a plurality of lever members forming a part of the invention; and

Fig. 6 is a plan view on a large scale of the coin-receiving means of the invention.

35 Referring now to the drawings more in detail, the invention will be fully described.

The meter preferably includes a housing 2 which may be supported in any suitable way, as by a standard 4. The housing 2 is hollow and there may be a door 6 overlying an opening therein, which door is preferably provided with a window 8 for a purpose later to appear. There is also an opening or slot in a side wall of the casing through which a coin-receiving member, described 45 below, projects.

There is a transparent dome 9 on the housing and a signal 10 is movable between an upper, signaling or visible position within the dome and a lower, non-signaling or non-visible position. At 50 the expiration of a predetermined period of time, according to the setting of the timing mechanism in a way described below, the signal is elevated to indicate that the paid-for parking time has expired while, as will appear, the insertion of a coin 55

will simultaneously set the timing mechanism and cause the signal to disappear.

A slotted plate member 12, preferably formed somewhat as shown in Fig. 4, receives and acts as a guiding slot for a coin or coins and this may be supported on a plate 11 within the housing. Said member 12 has a part projecting outwardly of the casing provided with an entrance opening or aperture such as 14 for the coin. If desired, of course, the arrangement could be such that the coin would be inserted in the outer end of the slot of the slotted member 12.

A means is provided to move the coin inwardly into the housing and into and through the member 12 and, according to the form shown, this means includes a handle or door member 16 having a recess 18 extending inwardly from a side thereof adjacent the casing within which is secured, as by rivet or pin 20, a coin-engaging part 22. Said part 22 preferably has its inner end notched as shown to provide spaced cam surfaces 24 and 26.

As will be seen, the construction is such that in closed position (Fig. 1) the door 16 covers up aperture 14 and protects it from the elements, while in open position (Fig. 6) the part 22 prevents insertion of an implement or the like endwise of member 12 which would cheat the device. The upward swinging movement of member 16 is limited by engagement of the upper edge of slot 18 and member 12.

The members 16 and 22 are pivoted to the apparatus for swinging movements relative thereto as on a pin 28 extending therethrough and through the upper part of the outwardly projecting portion of the coin-receiving member 12. When a coin is inserted in the slot and the handle swung downwardly, it is first engaged by the cam 26 and continued downward movement of the handle on pivot 28 brings about engagement of the coin and cam 24 so that the coin is urged inwardly.

A plunger member 30 is slidable within the member 12 and this has upper and lower cam surfaces 32 and 34 respectively on its outer or left-hand end. Inward movement of a relatively large coin will bring about engagement thereof with the higher cam 32 while the penny will engage the lower cam 34.

The coin receiving member 12 is provided with a discharge slot 36 in its lower side for allowing any coin to drop downwardly away therefrom whenever said coin is urged to a point above the slot. It will be obvious that since the higher cam 32 is forwardly, or to the left, of cam 34, an inwardly-moving larger coin will engage the plunger sooner than will a smaller coin.

Or in other words, a nickel will move plunger 30 to the right a greater distance, before it is discharged through slot 36, than will a penny moving in the same direction. Thus the coin of the smaller denomination, when actuated by the driving member 22, will move the driven member 30 a lesser distance than will the coin of greater value.

It is desirable that some means be provided to urge the plunger 30 to the left again as soon as the coin deposited has been discharged. This is so that the plunger is ready to be driven by another coin should the operator so desire and while this means may vary in form, in the embodiment shown, it includes a coiled spring 38 having opposite ends attached to the immovable member 12 and the slidable plunger 30.

For a purpose, which will immediately be described, the plunger 30 has an outwardly projecting pin 40 and it is to this that one end of

spring 38 may be attached. The other end of the spring may be attached to a pin 42 of member 12. The forward face of said member 12 is provided with a slot or cut-away portion, as shown, to expose the forward central portion of slide 38 and the pin 40 extends outwardly in said cut-away from member 38 as shown in Fig. 3.

There may, of course, be any number of cam surfaces on both part 22 and member 38. That is to say, the parts may be constructed to accommodate coins of varying sizes and it will be appreciated that the distance which plunger 30 is moved to the right will depend upon which cam of the plunger is engaged and the relation of that cam to the discharge slot.

On the rear side of the plate 11 is a time or clockwork mechanism indicated generally by 44 and of any well-known form. That is to say, the particular construction of the time mechanism is not important, it only being necessary that it include the usual timing mechanism consisting of gears and springs arranged in such a way that a shaft may be rotated in one direction to wind the mechanism so that it operates for a definite, predetermined length of time and will rotate in an opposite or unwinding direction as the mechanism runs down and the time period expires.

This shaft is shown at 46 and it preferably extends outwardly above the path of movement of slideable part 38. Fixed on this shaft are a plurality of levers, about to be described, arranged in such a way as to be capable of engagement by pin 40 when member 38 moves to the right.

One of the lever members is shown at 50 in Fig. 5 and this has a body part provided with an aperture 52 for receiving the shaft 46. This member is slotted at 54 so as to form a pair of spaced lever parts 56 and 58 as shown.

Another lever member is shown at 50 in Fig. 5 and this has a shaft-receiving opening 52. Formed to have spaced lever parts 64, 66 and 68, the member also preferably is provided with a rearwardly extending pin 69 for a purpose later to be apparent.

Still another lever member 70 is shown in Fig. 5 and this has a square opening 72 for receiving a squared portion of the clock's shaft 46 so as to be non-rotatable relative thereto. While the members 50 and 60 may be rotatable on shaft 46, it will be appreciated that since member 70 is not rotatable relative to the shaft any swinging movement of lever 70 will bring about rotation of the clock shaft.

Said member 70 is provided with an abutment 74 which is engaged by part 64 of lever 68 whenever the latter swings to the right so that lever member 70 is also swung to the right and shaft 46 is thereby rotated in a counter-clockwise direction. Members 50 and 60 are also preferably provided with abutments 55 and 65 respectively arranged for co-operative engagement so that when lever 50 is swung to the right member 60 and, by means thereof, member 70 are swung to the right.

The construction and arrangement of these levers are preferably such that when a penny is deposited to drive plunger 30 to the right, pin 40 will engage lever part 64, ride into slot 54, and urge said part 64 to the right a distance which will bring about sufficient rotation of shaft 46 to wind the clock for a parking period of, say, twelve minutes. If this is all the time desired, the operator will, of course, deposit no further coins and at the expiration of the period, the clock will have rotated its shaft in a clockwise direction.

direction, member 70 thereon will have urged member 60 and, therethrough, member 50 to the left, and the device is ready for another operator.

If, on the other hand, the operator desires a twenty-four minute parking period, he will deposit a second penny and the pin 40 will then engage lever 56 and urge it to the right so that the successive levers rotate shaft 46 to wind the clock for the desired period.

Again if an hour's parking is wished, the deposit of a nickel will cause the pin to engage lever 64 and move it to the right a greater distance so that shaft 46 is rotated the proper amount and lever 66 will be found adjacent pin 40. The immediate deposit of a second five-cent piece then will cause lever 66 to be moved to the right so that the clock is wound for a total of two hours.

Three hours of parking time may be obtained by employing a third nickel to drive pin 40 into engagement with lever 68 which, by reason of the construction shown, will then be adjacent said pin.

It is preferable that a coil spring 18 be provided to urge the successive lever members into the normal position shown in Fig. 3. This spring may have its opposite ends attached to abutment 55 on member 50 and an abutment 76 on member 70 and while it will allow any necessary relative rotation of members 50 and 60 and shaft 46, it will result in the levers returning to their desired abutting relationship after any rotation of the clock shaft so that the deposit of any subsequent coin will bring about the movement of fixed member 70 necessary to rotate the shaft the proper amount.

Pivoted on shaft 46 is a signal shifting lever 80. This normally is engaged by pin 69 and when the apparatus is not in operation, the parts are so arranged that said lever 80 is held in the position shown in Fig. 3.

In that position, the outer or free end of member 80 is in engagement with a crank portion 82 of a member 84 which is pivoted as on a pin 86 attached to plate 11. In this non-operating position of the parts controlling the clock-mechanism, said member 84 holds signal 10 in its elevated position.

If desired, the signal may be guided on a vertical support, such as rod 88, but in any event it will be seen that when the period of time paid for has expired and the clock has run down so that clockwise rotation of shaft 46 has brought the successive lever members to the position shown in Fig. 3, the signal is visible to indicate that a coin must be deposited before parking can be permitted. On the other hand, the setting in motion of the apparatus by the deposit of a coin will move lever 60 counter-clockwise so that pin 69 moves downwardly through an arc which permits lever 80 to move downwardly.

The member 84, since it rides on the free end of lever 80, will automatically swing downwardly on its pivot. This permits the signal to drop to a non-signalling position for the period of time paid for, only to appear again when the allotted time expires.

Projecting outwardly from the front face of plate 11 are a pair of spaced rib members 90 and 92. These members are below the coin-discharge slot 36 and so formed and arranged that a discharged coin C is guided to the position shown in Fig. 3. In this position the coin will be visible through window 8 so that counterfeits can be detected.

A discharged coin is held in this position, until another is discharged, by a member 94 which is slidable relative to a part 96 fixedly disposed adjacent the lower ends of ribs 90 and 92. That is, the member 94 is normally in the coin-engaging position shown in Fig. 3 and is moved therefrom only when a second coin is discharged.

This may be accomplished by a series of pivoted-together links 98, the upper of which is in the path of movement of pin 40, as shown, and the other of which has an end pivoted to slideable member 94. Preferably a spring 100 has opposite ends attached to said lower link and the supporting structure to urge the member 94 to its normal position.

It will be seen that according to my construction, a single coin chute is employed and this accommodates coins of varying denominations so that parking periods of various times may be obtained. Further, not only do I employ but a single coin chute for these various coins but there is but a single driving member and a single driven member.

That is to say, the arrangement is such that the same member 22 acts on the different sized coins and urges them against the same plunger which, in turn, is driven varying amounts depending upon the number of coins previously deposited and the denominations thereof.

The door 16 is so constructed that when in closed position it closes up the coin aperture and protects the same from rain, etc.

While I have described the invention in great detail and with respect to the present preferred form thereof, it is not desired to be limited thereto since changes and modifications may be made therein without departing from the spirit and scope of the invention. The invention may be embodied in other specific forms without departing from the essential characteristics thereof. The present embodiments are therefore to be considered in all respects as illustrative and not restrictive, the scope of the invention being indicated by the appended claims rather than by the foregoing description, and all changes which come within the meaning and range of equivalency of the claims are therefore intended to be embraced therein.

What it is desired to claim and secure by Letters Patent of the United States is:

1. Apparatus of the class described comprising in combination, a member having a longitudinally-extending open-ended coin-receiving slot and an entrance opening for coins adjacent the end of said member leading into said slot, an operating handle pivoted to said member adjacent said opening, a slide reciprocable in said slot, and a coin-engaging member carried by said handle having a part operable in said slot as said handle swings in one direction to act on a coin in said slot and cause the same to reciprocate said slide.

2. Apparatus of the class described comprising in combination, a chute member having a longitudinally-extending and horizontally-disposed open-ended coin-receiving slot, an operating handle adjacent said slot, a slide reciprocable in said slot, and a coin-engaging member carried by said handle having a part operable in said slot to act on a coin therein and cause the same to reciprocate said slide, said slide being formed to have one surface for actuating engagement by a coin of one dimension and another surface for actuating engagement by a coin of a different dimension.

3. In an apparatus of the class described the

- combination of, a chute member having a longitudinally-extending open-ended slot for receiving coins of varying dimensions and provided with an opening in its lower side spaced from the open end of the slot for permitting the gravitational discharge of any coin inserted, a coin-engaging member having a part movable in said slot for engaging any coin inserted in said open end thereof and moving it towards said opening, a slide longitudinally reciprocable within said slot arranged to be initially engaged by any inserted coin when the latter is moved towards said opening by said coin-engaging member, said slide being so formed and normally located with respect to said slot and coin-engaging member as to be reciprocated various distances according to the dimension of the particular coin which is inserted and acted upon by the coin-engaging member, said discharge slot being so located with respect to said coin-engaging member and slide as to permit discharge of each coin when the same has reciprocated the slide to the extent intended.
4. Apparatus of the class described comprising in combination, a member having a longitudinally-extending open-ended coin-receiving slot and an entrance opening for coins adjacent the end of said member leading into said slot, an operating handle pivoted to said member adjacent said opening, a slide reciprocable in said slot, a coin-engaging member carried by said handle having a part operable in said slot as said handle swings in one direction to act on a coin in said

slot and cause the same to reciprocate said slide, said handle being recessed and said coin-engaging member being pivoted therein.

5. Apparatus of the class described comprising in combination, a member having a longitudinally-extending open-ended coin-receiving slot and an entrance opening for coins adjacent the end of said member leading into said slot, an operating handle pivoted to said member adjacent said opening, a slide reciprocable in said slot, a coin-engaging member carried by said handle having a part operable in said slot as said handle swings in one direction to act on a coin in said slot and cause the same to reciprocate said slide, said part of said handle being provided with a plurality of cam surfaces arranged to engage coins of different dimensions.

6. Apparatus of the class described comprising in combination, a member having a longitudinally-extending open-ended coin-receiving slot and an entrance opening for coins adjacent the end of said member leading into said slot, an operating handle pivoted to said member adjacent said opening, a slide reciprocable in said slot, a coin-engaging member carried by said handle having a part operable in said slot as said handle swings in one direction to act on a coin in said slot and cause the same to reciprocate said slide, and means normally urging said slide in the direction of said entrance opening.

CHARLES H. MARTIN.
